UNITED STATES PATENT OFFICE

JAMISON R. HARRISON, OF MIDDLETON, CONNECTICUT

HIGH FREQUENCY GENERATOR CIRCUIT

Application filed July 31, 1928. Serial No. 296,583.

My invention relates to high frequency generator circuit arrangements in general and more specifically to circuit arrangements wherein high frequency signalling energy of a substantially constant frequency value is produced.

An object of my invention is to provide certain improvements in electron tube circuit arrangements for generating electrical oscillations of constant frequency.

Another object of my invention is to provide a balanced vacuum tube circuit arrangement wherein a plurality of vacuum tubes may be employed for producing high frequency oscillations of electrical energy.

Other and further objects of my invention will appear from the specification to follow and from the accompanying drawing wherein is illustrated the high frequency generator circuit arrangement of my invention.

In the accompanying drawing two electron tubes 1 and 2 are represented, each having filament electrodes 3 and 7, control grid electrodes 4 and 8, shielding grid electrodes 6 and 10 and plate electrodes 5 and 9. Filament electrodes 3 and 7 are energized by source 17. Control grid electrodes 4 and 8 are supplied with a source of biasing energy from source 18 through radio frequency choke coils 11 and 12 respectively. Source of energy 19 supplies a positive potential to shielding grid electrodes 6 and 10 and plate electrodes 5 and 9. Radio frequency choke coil 13 excludes radio frequency energy from source 19.

Inductance 14 and capacity 15 have frequency characteristics corresponding approximately to the frequency value of the desired generated frequency. A mechanically vibratile element 16 is employed for maintaining the circuit at a constant frequency value and has frequency characteristics corresponding to the approximate frequency characteristics of the common anode or plate circuit 14, 15. Conductive members

A, B, C and D are movable and arranged adjacent to mechanically vibratile element 16. Mechanically vibratile element 16 is herein illustrated as a crystal having piezo electric properties although it is obvious that any means may be employed capable of main-

taining oscillations of electrical energy at substantially constant frequency value. An adjustment *d* provides means for varying the phase relationship between the two input circuits and two output circuits.

Conductive members A, B, C and D are connected to electrodes 4, 8, 5 and 9 respectively. Adjustable contact member 20 provides means for adjusting the relative positive potential supplied shielding grid electrodes 6 and 10.

The control grid 4 and anode 5 of the electron tube 1 are connected to the conductive members A and C respectively which are adjacent to the same face of the piezo electric element 16. Likewise the conductive members B and D adjacent to the opposite side of the element 16 are connected to the control grid 8 and anode 9 of the electron tube 2. When a stress is set up in the element 16 the resulting polarization induces electrical charges of opposite sign on the metallic conductive members adjacent to the two opposite faces of the element 16. Conductive members A and C, when connected to electrodes 4 and 5, will receive charges of the same sign and likewise the conductive members B and D will have charges of like sign but which are opposite in sign to the charges on A and C. When the control grid 4 of vacuum tube 1 is supplied with a positive potential the control grid 8 of electron tube 2 is supplied with a negative potential. Because of these opposite grid charges, the current in the anode circuit of electron tube 1 will be increasing at the same time that the current in the anode circuit of tube 2 is diminishing. However, anodes 5 and 9 are connected to the opposite ends of the inductance coil 14 and the direction of these currents, as illustrated by the arrows 22 in the output circuit, is such as to produce an additive effect.

It is obvious that many modifications of the high frequency generator circuit of my invention are possible without departing from the spirit of my invention and it is to be understood that my invention is not to be limited to the foregoing specification or to the accompanying drawing but only as defined in the appended claims.

What I claim as new and desire to secure by Letters Patent of the United States is as follows:

1. An electron tube balanced circuit arrangement comprising in combination a plurality of electron tubes having grid, filament, plate and shielding grid electrodes, a mechanically vibratile means having a plurality of conductive members adjacent opposite sides thereof, said conductive members on one side connected to said grid and plate electrodes respectively of one branch of said balanced arrangement and said conductive members adjacent the opposite side thereof connected 15 to said grid and plate electrodes respectively of the other branch of said balanced circuit arrangement.
2. In a generator of high frequency oscillations, in combination, two thermionic electron tubes each having grid, filament, plate, and shielding grid electrodes, sources of filament potential, plate potential, grid biasing potential and shielding grid biasing potential, a piezo-electric crystal element, two pairs of electrodes spaced from each other and in electrical relation with said piezo-electric crystal, the electrodes constituting a pair being positioned substantially opposite each other, a load connected to said plate electrodes, a 20 balanced circuit system connecting said electrodes in such manner that each electrode of one pair of piezo-electric crystal electrodes is connected to one of said grid electrodes, each electrode of said other pair of piezo-electric crystal electrodes is connected to one of said plate electrodes, said shielding grid electrodes are connected together and to said source of shielding grid biasing potential, and said source of grid biasing potential biases the 25 potential of both of said grid electrodes with reference to both of said filament electrodes.
3. In a generator of high frequency oscillations, in combination, a plurality of electron tubes arranged in two symmetrical groups, each tube having grid, filament, plate, and shielding grid electrodes, sources of filament potential, plate potential, grid biasing potential, and shielding grid biasing potential, a piezo-electric crystal element, two pairs of electrodes spaced from each other and in electrical relation with said piezo-electric crystal, the electrodes constituting a pair being positioned substantially opposite each other, a load connected to said plate electrodes, a 30 balanced circuit system connecting said electrodes in such manner that each electrode of one pair of piezo-electric crystal electrodes is connected to the grid electrodes of one of said groups, each electrode of said other pair 35 of piezo-electric crystal electrodes is connected to the plate electrodes of one of said groups, said shielding grid electrodes are connected together and to said source of shielding grid biasing potential, and said source of grid biasing potential biases the potential of all of 40 said grid electrodes with reference to all of said filament electrodes.
4. In a generator of high frequency oscillations, in combination, a plurality of electron tubes arranged in two symmetrical groups, each tube having grid, filament, plate, and shielding grid electrodes, sources of filament potential, plate potential, grid biasing potential, and shielding grid biasing potential, a piezo-electric crystal element, two pairs of electrodes spaced from each other and in electrical relation with said piezo-electric crystal, the electrodes constituting a pair being positioned substantially opposite each other, a load connected to said plate electrodes, a balanced circuit system connecting said electrodes in such manner that each electrode of one pair of piezo-electric crystal electrodes is connected to the grid electrodes of one of said groups, each electrode of said other pair of piezo-electric crystal electrodes is connected to the plate electrodes of one of said groups, said shielding grid electrodes are connected together and to said source of shielding grid biasing potential, and said source of grid biasing potential biases the potential of all of said grid electrodes with reference to all of said filament electrodes.
5. In a generator of high frequency oscillations, in combination, a plurality of electron tubes arranged in two symmetrical groups, each tube having grid, filament, plate, and shielding grid electrodes, sources of filament potential, plate potential, grid biasing potential, and shielding grid biasing potential, a mechanically vibratile element, two pairs of electrodes spaced from each other and in electrical relation with said mechanically vibratile element, the electrodes constituting a pair being positioned substantially opposite each other, a load connected to said plate electrodes, a balanced circuit system connecting said electrodes in such manner that each electrode of one pair of vibratile element electrodes is connected to the grid electrodes of one of said groups, each electrode of said other pair of vibratile element electrodes is connected to the plate electrodes of one of said groups, said shielding grid electrodes are connected together and to said source of shielding grid biasing potential, and said source of grid biasing potential biases the potential of all of said grid electrodes with reference to all of said filament electrodes.
6. In a generator of high frequency oscillations, in combination, a plurality of electron tubes arranged in two symmetrical groups, each tube having grid, filament, plate, and shielding grid electrodes, sources of filament potential, plate potential, and

said grid electrodes with reference to all of said filament electrodes.

4. In a generator of high frequency oscillations, in combination, a plurality of electron tubes arranged in two symmetrical groups, each tube having grid, filament, plate, and shielding grid electrodes, sources of filament potential, plate potential, grid biasing potential, and shielding grid biasing potential, a piezo-electric crystal element, two pairs of electrodes spaced from each other and in electrical relation with said piezo-electric crystal, the electrodes constituting a pair being positioned substantially opposite each other, a load connected to said plate electrodes, a balanced circuit system connecting said electrodes in such manner that each electrode of one pair of piezo-electric crystal electrodes is connected to the grid electrodes of one of said groups, each electrode of said other pair of piezo-electric crystal electrodes is connected to the plate electrodes of one of said groups, said shielding grid electrodes are connected together and to said source of shielding grid biasing potential, and said source of grid biasing potential biases the potential of all of said grid electrodes with reference to all of said filament electrodes, and means for varying the spacing between said two pairs of piezo-electric crystal electrodes, whereby the oscillations generated may be controlled.

5. In a generator of high frequency oscillations, in combination, a plurality of electron tubes arranged in two symmetrical groups, each tube having grid, filament, plate, and shielding grid electrodes, sources of filament potential, plate potential, grid biasing potential, and shielding grid biasing potential, a mechanically vibratile element, two pairs of electrodes spaced from each other and in electrical relation with said mechanically vibratile element, the electrodes constituting a pair being positioned substantially opposite each other, a load connected to said plate electrodes, a balanced circuit system connecting said electrodes in such manner that each electrode of one pair of vibratile element electrodes is connected to the grid electrodes of one of said groups, each electrode of said other pair of vibratile element electrodes is connected to the plate electrodes of one of said groups, said shielding grid electrodes are connected together and to said source of shielding grid biasing potential, and said source of grid biasing potential biases the potential of all of said grid electrodes with reference to all of said filament electrodes.

6. In a generator of high frequency oscillations, in combination, a plurality of electron tubes arranged in two symmetrical groups, each tube having grid, filament, plate, and shielding grid electrodes, sources of filament potential, plate potential, and

shielding grid biasing potential, a piezo-electric crystal element, two pairs of electrodes spaced from each other and in electrical relation with said piezo-electric crystal, the electrodes constituting a pair being positioned substantially opposite each other, a load connected to said plate electrodes, a balanced circuit system connecting said electrodes in such manner that each electrode of 5 one pair of piezo-electric crystal electrodes is connected to the grid electrodes of one of said groups, each electrode of said other pair of piezo-electric crystal electrodes is connected to the plate electrodes of one of said groups, 10 and said shielding grid electrodes are connected together and to said source of shielding grid biasing potential.

In testimony whereof I affix my signature.
